To all whom it may concern:

Be it known that I, CEDELIA M. Figure 1 represents a plan view, and Fig. 2 represents an elevation.

The leading feature of my design consists in the rectangular shape of the table, provided with the several compartments thereof, and the extended portion of the same having the circular opening near the margin, as shown.

Referring to the drawings, in which similar

B and D represent extended clothes or towel rack.

E represents the main body of the table, having the oblong compartments of varying sizes 25 e e, as shown. These compartments, like the table, are rectangular or square in outline.

F F indicate leaves or cover.

Having thus described my design, what I claim is—
